(57) **CLAIM**

The ornamental design for a display screen or portion thereof with set of icons, as shown and described.

DESCRIPTION

The sole FIGURE shows a display screen or portion thereof with set of icons showing our new design.

The peripheral dashed broken lines illustrate a display screen or portion thereof, and form no part of the claimed design.

The solid line bracket indicates a set. The elements of the set are arranged relatively on the drawing sheet for the convenience of illustration, and the placement of each element relative to another, or to the drawing sheet, forms no part of the claimed design.
